[57] CLAIM

The ornamental design for a blanket rack, as shown and described.

DESCRIPTION

FIG. 1 is a side perspective view of a blanket rack showing my new design;

FIG. 2 is a left side elevational view thereof;

FIG. 3 is a right side elevational view thereof;

FIG. 4 is a bottom plan view thereof;

FIG. 5 is a top plan view thereof; and,

FIG. 6 is a front elevational view thereof, the rear elevational view being a mirror image of that shown.
